CONVEYER

Edwin H. Allfree, Ironton, Ohio

Application February 25, 1932. Serial No. 595,201

8 Claims. (Cl. 198—220)

This invention relates to the loading and transportation of materials and comprises a structure which combines, within itself, functions and operations hitherto accomplished by two different 5 types of machines, namely, power shovels and oscillating conveyers.

This invention, which hereinafter, for convenience, I shall term a "shaker shovel", is primarily adapted for use in mines, and consists of a 10 structure so designed, constructed and operated that it performs the digging and loading work heretofore accomplished by power shovels together with the transportation of the material formerly performed by oscillating conveyers.

15 The objects of the invention are as follows: *First.*—To construct a device of the character specified in such a manner that it comprises a mobile unit capable of transport from place to place, under its own power, without disassembling 20 of parts.

25 *Second.*—To construct the device in such a manner that while one half of the oscillating members of the conveyer are engaged in forward movement the other half are engaged in rearward movement and vice versa, whereby the forces of inertia are divided and opposed, in approximately equal amounts, with a consequent elimination of vibration to such a substantial degree as to render unnecessary the rigid mounting 30 and bracing heretofore essential in conveyers of similar type.

35 *Third.*—The provision of means integral with the device, for effecting the desired opposed movement of the members of the oscillating conveyer.

40 *Fourth.*—The provision of means integral with the device and operative at will, for moving it from place to place.

45 *Fifth.*—The provision of improved connecting means between adjacent sections in the conveyer train.

50 *Sixth.*—The provision of improved supporting means for the sections in the conveyer train.

55 *Seventh.*—Other objects and advantages of the invention will fully appear and will be readily understood from the following detailed description of the construction and cooperation of the parts.

These objects are attained in the manner 50 hereinafter set forth, reference being had to the accompanying four sheets of drawings, wherein similar reference characters indicate the same parts in the several figures.

The invention consists of structural character- 55 istics and relative arrangement of elements to be

hereinafter more fully described and particularly pointed out in the appended claims.

In the drawings:

Figure 1 is a top plan view, somewhat diagrammatic in nature, of a shaker shovel constructed 60 in accordance with and embodying the principles of this invention;

Figure 2 is a similar view, on a somewhat larger scale than Figure 1, of the central portion of the device and illustrating in greater detail the power 65 plant thereof;

Figure 3 is a side view of the parts shown in Figure 2;

Figure 4 is a similar side view of the shovel or digging end of the device;

Figure 5 is a greatly enlarged vertical sectional view on the line V—V of Figure 2 and illustrating the means employed for imparting reciprocating movement to the members of the oscillating conveyer;

Figure 6 is a horizontal sectional view on the line VI—VI of Figure 5;

Figure 7 is a diagrammatic view illustrating the sequence of variation in oscillating velocity of the conveyer members and the opposition of 80 the forces of inertia to obtain approximate balance;

Figure 8 is a vertical sectional view on the line VIII—VIII of Figure 2 and illustrating the means employed for moving the device from place to 85 place;

Figure 9 is a top plan view of one end of a conveyer member illustrating the supporting means therefor and the connecting means adapted to secure it to the end of an adjacent member in 90 the conveyer train;

Figure 10 is a side view, partly broken away, of the parts shown in Figure 9;

Figure 11 is a vertical sectional view on the line XI—XI of Figure 10;

Figure 12 is a view similar to a portion of Figure 10, but illustrating also the cooperating end of the adjacent member of the conveyer train with the connecting means of the two members in engaged position;

Figure 13 is a sectional plan view on the line XIII—XIII of Figure 12;

Figure 14 is a top plan view similar to a portion of Figure 1, and illustrating certain means by which the shovel at the digging end of the 105 device may be swung from side to side;

Figure 15 is a greatly enlarged vertical sectional view on the line XV—XV of Figure 14; and,

Figure 16 is a side view of the parts shown in Figure 15.

11

Briefly stated, this invention contemplates the use of a series of conveyer members connected together to two trains of substantially equal length and weight and adapted to overlap at their meeting point. Means are provided, preferably at this meeting point, for causing simultaneous oscillatory movement of the trains but in opposite directions. At the outer end of the material receiving train is connected a shovel member adapted to oscillate with that train. The invention further contemplates the mounting of the conveyer members upon a train of connected wheeled trucks in such manner that they are reciprocable in respect thereto so that during the oscillations of the trains of conveyer members the train of trucks is motionless. Finally, the train of trucks is mounted upon a track and power means, preferably associated with the conveyer oscillating means, is provided to actuate driving mechanism whereby the train of trucks and conveyers carried thereby may be moved, as a unitary structure, from place to place upon the rails.

Referring, in the first instance, to Figures 1, 2, 3 and 4 of the drawings, there is shown a shaker shovel comprising a central power unit A, a material conveyer train B, and a material delivery conveyer train C.

The power unit A embodies a platform 21 supported as a truck upon two pairs of wheels 22 on axles 23. A motor 24 is mounted upon the platform 21 and its shaft 25 is provided with a pair of worm gears 26 meshing with worms 27 on the wheel axles 23, as shown in detail in Figure 8. The wheels 22 are of the conventional flanged type and engage rails 28 so that when the motor 24 is operated the platform 21 will be driven to or fro upon the railway. Operation of the motor 24 is effected through the medium of a controller 29 of any desired type.

Also mounted upon the platform 21 of the power unit A is a motor 31 adapted to actuate the members of the oscillating conveyer trains B and C. The shaft 32 of this motor 31 operates worm gearings, the positions of which are indicated at 33 and 34 in Figures 1 and 2, and which are shown in detail in Figure 5. Each of these gearings comprises a worm 35 on the shaft 32 which meshes with a worm gear 36 secured to a vertical shaft 37 rotatably mounted in a bearing structure carried by the platform 21. At the base of each shaft 37 is a head 38 from which projects downwardly a crank pin 39 engaging one end of a link 41, which in turn is engaged at its other end by one arm of a lever 42 pivotally mounted upon a vertical stud 43 mounted on a supporting structure carried by the platform 21.

The other arm of the lever 42, which is actuated by the gear mechanism indicated at 33 in Figures 1 and 2, is connected to a conveyer member 44, which is the inner or last member in the material receiving conveyer train B. The corresponding arm of the similar lever 42, which is actuated by the gear mechanism indicated at 34 in Figures 1 and 2, is connected to a conveyer 45, which is the inner or first member in the material delivery conveyer train C. The adjacent ends of the members 44 and 45 are at all times in overlapping relation to each other so that material discharged from the conveyer train B will be received by the conveyer train C in a manner to be later described.

The material receiving conveyer train B consists of a plurality of connecting members 46 and mounted members 47 pivotally connected to-

gether to form an articulated whole. Similarly, the material delivery conveyer train C consists of a plurality of similar connecting members 46 and mounted members 47, which are likewise pivotally connected together to form an articulated whole.

Each mounted member 47 is reciprocably mounted upon a wheeled truck 48 mounted upon the tracks 28 and adjoining trucks of each train are pivotally connected to each other and the trains of trucks are pivotally connected to the platform 21 of the power unit A by means of draw bars 49. Thus, it will be seen that the trucks form articulated trains corresponding, in articulation, to the conveyer trains, and the manner in which the entire device may be driven from place to place, under its own power, wherever the tracks extend, is self-evident and calls for no further description.

The mounted member 47 at the outer end of the conveyer train B, remote from the power unit A, is fixedly mounted upon its truck 48 rather than reciprocable thereupon and at its outer end has hingedly and detachably secured to it a scoop or shovel 51 adapted, under the influence 100 of the oscillation of the conveyer train, to dig into, pick up and feed along any material upon a pile or collection on which it may be brought to bear. The manner in which this scoop or shovel 51 is secured to the end member 47 is, 105 preferably, as illustrated in detail in Figures 15 and 16, wherein it is shown that the member 47 is provided with a pair of laterally spaced knuckles 52, the shovel 51 is provided with a centrally disposed offset knuckle 53 and union 110 is effected by means of a laterally removable coupling pin 54 which engages with all three of the knuckles.

When the device is in operation, it may frequently be desirable to swing the shovel 51 from 115 side to side without disturbing the position of the rest of the structure. This may readily be effected, especially when the device is located at a dead end of track, as it most usually will be, in the manner shown in Figure 14. In this view, 120 the track is shown as having its rails equipped with block-and-tackle structures 55 and 56, the outer pulleys 57 of which are fixedly mounted with respect to the normal position of the rails. Tension upon the cable of one block-and-tackle 125 structure coupled with corresponding slackening of the cable of the other structure will move the track to one side or the other with consequent swing from side to side of the path of operation of the shovel 51. The tension and slackening of 130 the cables may be effected by hand, or it may be power controlled from the power unit A in a manner so obvious as to require no specific illustration.

In the operation of the device, the motor 31 135 causes oscillation of the levers 42 through the medium of the interposed worm gearings, shafts, crank pins, and links. The two crank pins 39 are so positioned, rotatively, in respect to one another that the movements of the levers are 140 opposed. That is to say, the conveyer train B is caused to oscillate forwardly towards the power unit A during the time that the conveyer train C is caused to oscillate rearwardly towards the power unit and vice versa. Thus, the forwardly 145 exerted force of inertia of the train B will be met and substantially neutralized by the simultaneous rearwardly exerted force of inertia of the train C, and the rearwardly exerted force of inertia 150 of the train B will be met and substantially neu-

tralized by the simultaneous forwardly exerted force of inertia of the train C. Inasmuch as the two trains are designed to be of practically equal length and weight, this neutralization of inertia strains and stresses, while not by any means one hundred per cent, is of such a great degree that vibration is reduced to a point where the device is practically self supporting and requires no outside bracing or anchorage. As a further result of the elimination of disturbing forces or undesirable vibration, the device may traverse and operate over lightly constructed trestles, a feature which has hitherto been impossible with oscillating conveyers for the reason that such trestles could not withstand the great vibration inherent to such conveyers.

The reason that vibration can not be wholly eliminated and the inertia forces caused to completely neutralize each other is that the forward and backward oscillations of the conveyor trains B and C, while opposed and rhythmic, are not harmonious. In order to effect maximum forward feed of the material under transportation, each forward swing of each conveyer train is characterized by slowly accelerated and rapidly retarded motion, and each backward swing of each conveyer train is characterized by rapidly accelerated and slowly retarded motion. Thus, as the reciprocations of the two trains are opposed, slow acceleration of one train will always be opposed by rapid acceleration of the other, and rapid retardation of one will always be opposed by slow retardation of the other, and vice versa, and these will always be a preponderance of inertia force exerted in one direction or the other with a certain amount of consequent vibration, but the terrific surges and pulsations, heretofore an inescapable concomitant of operation of oscillating conveyers, have been overcome to a point where they are negligible.

The timing and sequence of acceleration and retardation during the oscillations of the conveyer trains are illustrated, diagrammatically, in Figure 7. The two crank pins controlling the oscillations are shown at x and y, diametrically opposed and as though revolving about a common center z. The two links are shown at m and n. The velocity of oscillation of the conveyer trains at one stage of their movement is as the length of the line a, and at the opposite stage of their movement it is as the length of the line b.

The crank pins rotate with uniform speed and, due to the angular disposition of the links, the desired variations in velocity of oscillation of the conveyer trains is established and maintained.

The manner in which the conveyer members 47 are supported upon the trucks 48 so as to be capable of reciprocation in respect thereto is best shown in Figures 9, 10 and 11.

Each truck 48 consists of a platform 61, side frames 62 and wheels 63 rotatably mounted on axles 64. The axles are fixedly secured to the body of the truck by means of U-bolts 65. Secured to the platform 61 are pairs of laterally spaced rails 66 upon which rest rollers 67 secured, in pairs, to shafts 68. Resting upon the upper faces of the rollers 67 are pairs of laterally spaced rails 69 secured to the under face of the conveyer member 47. When the conveyer member trains are oscillated, the rails 69 run upon the rollers 67 which, in turn, run upon the rails 66, and the supporting trucks thus provide a fixed and motionless support for the oscillating conveyer trains. Accidental vertical or lateral dislodgement of the conveyer members from

the trucks is prevented by means of retaining plates 71, detachably secured to the upper faces of the side frames 62 of the trucks. Any tendency towards slipping of the supporting rollers 67 between the rails 66 and 69 is prevented by means of certain positive rack and spur connection therebetween. Adjacent each rollers 67 and preferably formed integrally therewith is a spur pinion 72. Adjacent each rail 66 and preferably formed integrally therewith is a rack 73. And adjacent each rail 69 is a similarly formed rack 74. While the weight of the members 47 is always supported by the rollers 67, the spurs 72 are constantly in mesh with the racks 73 and 74 and the proper relation between the conveyer member and supporting truck is insured.

In order that the device may be moved over the track from place to place, it is necessary that both the conveyer member trains and the supporting truck train be similarly articulated, as previously described. This is best accomplished by providing the adjacent conveyer members and adjacent truck and draw bars with vertically aligned couplings or connecting means. These are preferably provided in the manner shown in Figures 9, 10, 12 and 13. Secured to one of two abutting members of the conveyer train, or truck and draw bar train is a projecting arm 75 terminating in vertically spaced jaws 76 between which is mounted a ball or roller 77. Secured to the adjacent member of the corresponding train is a swinging hook 78 adapted to encircle and embrace the ball or roller 77, as shown in Figure 13. This hook 78 terminates in a forked outer end 79. Laterally spaced from the pivot of the swinging hook 78 is the pivot of a swinging bolt 81, upon the outer end of which is threaded a nut 82.

In coupling, adjacent members of the two trains are brought into proper position. First, the two vertically aligned hooks 78 are swung to embrace the two vertically aligned balls or rollers 77, and then the two vertically aligned bolts 81 are swung to pass between the jaws of the forked outer ends 79 of the hooks 78. Finally, the nuts 82 are tightened and members of the train are thus properly connected. In uncoupling, the nuts 82 are loosened after which the hooks 78 are free to be swung to disengage the balls or rollers 77.

Any wear between the engaging members of the coupling device may be readily compensated by adjustment of the nuts 82, and slackness or lost motion is thus prevented.

From the foregoing disclosure of the construction and operation of the invention, it will be readily seen that all the objects and advantages recited in the statement of invention have been fully and efficiently carried out, in order to effect; first, an improved and efficient control of inertia in conveyers of the reciprocative type; second, to provide a conveyer capable of locomotion, or mounted on wheels for removal intact from place to place over railway tracks; third, an improved roller support for shaker conveyer troughing not only useful for railway mounting but adaptable for use elsewhere; fourth, a power shovel with means for locomotion capable of digging loose material and moving it over relatively long longitudinal distances not restricted to a straight path; and, fifth, such a reduction of vibration of supporting structures for shaker conveyers so that they may be safely mounted upon trestles or other desired carrying means, thereby extending their scope of usefulness and eliminating the use of powerful and expensive retaining jacks wedged between the top.

and bottom of mine tunnels now usually employed.

While the practical embodiment of this invention, which is herein illustrated and described, is the preferred form, it must be understood that it is in no sense a limitation of the invention. Many changes, alterations and modifications of the various parts and their relation to one another will readily suggest themselves to those skilled in the art, and it is contemplated that this invention includes all such changes, alterations and modifications as are in accordance with the principles of the invention as herein set forth and such as fall within the scope of the following claims.

What I claim is:

1. The combination, in a material conveying device, of a mobile power unit, a pair of mobile trains of supporting members coupled thereto and extending, respectively, forwardly and rearwardly therefrom, a pair of trains of conveyer members supported, respectively, upon said trains of supporting members but reciprocable in respect thereto, means carried by said mobile power unit for oscillating said conveyer trains simultaneously but in opposite directions, and means carried by said mobile power unit for moving itself and said mobile trains of supporting members.

2. The combination, in a material conveying device, of a plurality of conveyer members and means for connecting said members, end to end, to form a train, said connecting means including a projecting portion on one conveyer member terminating in a ball, a pivotally mounted hook on an adjacent conveyer member adapted to embrace said ball, and pivotally mounted means for retaining said hook in ball embracing position.

3. The combination, in a material conveying device, of a reciprocatory conduit comprising two sections of a plurality of connected elements, a railway track, trucks on said track for reciprocally supporting said conduit on said track, means for bodily moving said trucks with the conduit on said track, means carried by one of said trucks and attached to the adjacent ends of said two sections so constructed and arranged to reciprocate said sections in rectilinear paths and in such a manner that the reciprocations of one section are opposite in direction to the reciprocations of the other section, and all the elements of the conduit conveying the material in the same direction and said reciprocations being characterized by slowly accelerated rapidly retarded velocity alternating with rapidly accelerated slowly retarded velocity and in a definite and fixed relation to each other and in relation to said supporting trucks.

4. The combination, in a material conveying device, of a reciprocatory conduit comprising two sections of a plurality of separate connecting and supporting members, means for flexibly securing said connecting members to said supporting members to form an articulated whole, railway trucks, said supporting members reciprocably carried upon said trucks, means for flexibly securing said trucks coincident with the means for flexibly connecting said supporting members of the conduit so that the trucks form an articulated train corresponding in articulation to the conveyer train consisting of said flexibly secured two sections of connecting and supporting members, means carried by one of said trucks and connected to the adjacent ends of said two sections and so constructed and arranged to reciprocate one section on said trucks in opposite

direction to the reciprocation of the other section, and all the elements of the conduit conveying the material in the same direction, and said reciprocations being characterized by slowly accelerated rapidly retarded velocity alternating with rapidly accelerated slowly retarded velocity and in a definite and fixed relation to each other and in relation to said trucks.

5. The combination, in a material conveying device, of a reciprocatory conduit comprising two sections of substantially equal weight adapted to overlap at their adjacent ends and moving in rectilinear paths, means for reciprocally supporting said sections, a motor, oscillating means moving in a horizontal plane and so constructed, arranged and directly and independently connected to each of the adjacent ends of said sections and with said motor for reciprocating said two sections of said conduit with slowly accelerated rapidly retarded advance strokes alternately with rapidly accelerated slowly retarded return strokes in a definite and fixed relation to each other and to said supporting means, said advance strokes of one section of the conduit occurring during the return strokes of the other section.

6. The combination, in a material conveying device, of a reciprocatory conduit comprising two sections of substantially equal weight and moving in rectilinear paths, means for reciprocally supporting said sections, two separated pivotally mounted levers oscillating in a horizontal plane, one of said levers having one of its ends connected to one of the adjacent ends of said sections, and the other lever having one of its ends connected to the adjacent end of the other section, a motor, means connected to said motor so constructed, arranged and interconnected with the other ends of said two separated pivotally mounted levers for reciprocating said two sections of said conduit with slowly accelerated rapidly retarded advance strokes alternately with rapidly accelerated slowly retarded return strokes in a definite and fixed relation to each other and in relation to said supporting means, said advance strokes of one section of the conduit occurring during the return strokes of the other section.

7. The combination, in a material conveying device, of a reciprocatory conduit comprising two sections of substantially equal weight adapted to overlap at their adjacent ends and moving in rectilinear paths, means for reciprocally supporting said sections, two separated pivotally mounted levers oscillating in a horizontal plane, one of said levers having one of its ends connected to one of the adjacent ends of said sections, and the other lever having one of its ends connected to the adjacent end of the other section, and the other end of each of the pivotally mounted levers being provided with a link, a motor in proximity to the adjacent ends of said sections, means connected to said motor and each of said links pivoted to said levers for reciprocating said two sections of said conduit with slowly accelerated rapidly retarded advance strokes alternately with rapidly accelerated slowly retarded return strokes in a definite and fixed relation to each other and in relation to said supporting means, said advance strokes of one section of the conduit occurring during the return strokes of the other section.

8. The combination, in a material conveying device, of a reciprocatory conduit comprising two sections of substantially equal weight adapted

to overlap at their adjacent ends, means for reciprocally supporting said sections, a motor, oscillating means moving in a horizontal plane and so constructed, arranged and directly and independently connected to each of the adjacent ends of said sections and with said motor for reciprocating said two sections of said conduit with slowly accelerated rapidly retarded ad-

vance strokes alternately with rapidly accelerated slowly retarded return strokes in a definite and fixed relation to each other and to said supporting means, said advance strokes of one section of the conduit occurring during the return strokes of the other section. 80
